UNITED STATES PATENT OFFICE.

WADE SCHLARBAUM, OF MOUNT PLEASANT, IOWA.

MAIL BOX.

1,404,703.

Specification of Letters Patent. Patented Jan. 24, 1922.

Application filed July 27, 1920. Serial No. 399,272.

To all whom it may concern:

Be it known that I, WADE SCHLARBAUM, a citizen of the United States of America, and resident of Mount Pleasant, in the 5 county of Henry and State of Iowa, have invented certain new and useful Improvements in Mail Boxes, of which the following is a specification.

This invention relates to mail boxes and 10 particularly to a type of mail boxes which are used for rural mail collection and delivery.

An object of this invention is to produce a mail box having novel means whereby a 15 carrier may expeditiously remove mail from a box or deposit mail in a box so that the mail while being handled in its deposit or removal will not become displaced or dislodged from the box, even though there is 20 heavy wind pressure.

The invention has for its object furthermore the provision of a device associated with mail boxes that operates as a safety element to prevent mail from becoming 25 soiled by reason of its being dislodged from the receptacle, and the device furthermore results in reducing the time consumed by a carrier in depositing mail or removing it from the box, as the operator may use the 30 same hand for depositing and removing mail and at the same time close the box without removing hand covering such as mittens.

A still further object of this invention is to produce a device which will support the 35 mail in a box in such position that it cannot fail being observed by the carrier and hence there is no liability of mail being left behind through failure to detect it.

A further object of this invention is to 40 produce a device of the character indicated which is associated with the door or closure of a box and preferably movable with it so that the mail carrying member is brought into convenient position for depositing or 45 removing mail and in plain view of the carrier.

With the foregoing and other objects in view, the invention consists in the details of construction and in the arrangement and 50 combination of parts to be hereinafter more fully set forth and claimed.

In describing the invention in detail, reference will be had to the accompanying drawings forming part of this specification

wherein like characters denote corresponding parts in the several views, and in which—

Figure 1 illustrates a view in elevation of one form of letter box having the invention applied thereto;

Figure 2 illustrates a sectional view on the line 2—2 of Fig. 1;

Figure 3 illustrates a perspective view of the mail clamping elements;

Figure 4 illustrates a detailed view of one end of one of the clamping jaws.

In these drawings 10, denotes an approximately U-shaped mail box or receptacle having an inclined upper edge and an opening in the top through which mail may be deposited. A cover 11 has ears 12 at the ends, 70 the said ears being mounted on a pivot 13 so that the said lid may open and close the box as fully shown in Figure 2. The cover has a depending flange 14 at its rear edge which forms a water shield and it is bent to 75 the angle or the upper portion of the rear wall of the receptacle.

A mail holding or clamping element comprises a plate 16 having a flange 17 at its end standing at an angle to the plate so that the 80 plate may fit against the under surface of the cover and the flange, and the flange will conform to the contour of the depending flange of the cover, the said flange of the plate being secured to the flange of the cover 85 by fastenings 18 such as rivets or the like.

The plate has an extension 19 forming a jaw which is relatively rigid so that it will withstand pressure of a coacting jaw 20 and serve to retain mail which may be deposited 90 between the extension 19 and the jaw 20. The extension has a notch 21 at its outer end which forms a clearance so that an operator may insert a finger or a portion of his hand to press against the jaw 20 to separate it 95 from the extension 19 to create an opening for the insertion of mail.

As shown in the drawing the jaw 20 has ears 22 and the extension 19 has ears 23 which extend partially across each other, 100 and the jaw 20 is pivotally mounted by the pintle 24 which extends through the ears 22 and 23, the said pivoted jaw being urged against the extension 19 by a spring 25 which encircles the pivot and is arranged to 105 exert pressure to yieldingly hold the jaw in engagement with the extension.

By reason of the arrangement shown and

described the owner of the mail box may deposit mail therein for the carrier so that when the box cover is open, the mail will be elevated out of the box and presented in 5 convenient position for its removal from the holder, whereas the carrier can likewise deposit any mail which he may have after removing that which is to be collected, and the owner of the box will likewise have the mail 10 displayed to him upon opening the box.

The construction, operation and advantages, as well as the functions of the elements have been stated in connection with a 15 description of the elements and a résumé of the operation of the device is believed to be unnecessary, as the construction and arrangement of parts will, it is thought, be apparent by one skilled in the art.

I claim:

20 The combination with a mail box having

an opening, a movable cover for said opening and a depending flange formed at the rear edge of said cover, of a plate upon the interior of said cover, having a flange at its end standing at an angle to the plate and 25 secured to the depending flange of the cover, an oblique extension on said plate opposite the flange forming a relatively rigid jaw, a movable jaw opposite the rigid jaw, ears formed on said jaws adjacent the inner ends 30 thereof, a pintle extending through said ears, a coil spring on said pintle and exerting its tension on the movable jaw to retain said jaw in normal contacting relation with the rigid jaw and the rigid jaw having a 35 notch through its outer end opening onto the movable jaw to facilitate the actuation of said movable jaw.

WADE SCHLARBAUM.
